Patented July 19, 1910.

UNITED STATES PATENT OFFICE.

HARRY O. RUGH, OF SANDWICH, ILLINOIS, ASSIGNOR TO SANDWICH ELECTRIC COMPANY, OF SANDWICH, ILLINOIS, A CORPORATION OF ILLINOIS.

SELECTIVE SIGNALING SYSTEM.

Specification of Letters Patent. Patented July 19, 1910.

965,017.

Application filed February 15, 1909. Serial No. 476,085.

To all whom it may concern:

Be it known that I, HARRY O. RUGH, citizen of the United States, residing at Sandwich, in the county of Dekalb and State of Illinois, have invented a certain new and useful Improvement in Selective Signaling Systems, of which the following is a full, clear, concise, and exact description, reference being had to the accompanying drawings, forming a part of this specification.

My invention relates to signaling systems, and more particularly to signaling systems as applied for use along a railway right-of-way, and has for its object the provision of an improved device for selectively calling the various stations from a central office.

I will describe my invention more in detail by reference to the accompanying drawings illustrating the preferred embodiment thereof. I have there shown a line circuit consisting of the line wires 1 and 2, which unites the central station A with the various substations B, C and D. The line wires 1 and 2 are joined at both extremities through impedance coils 3 and 4, which impedance coils are designed to prevent the passage therethrough of telephonic currents in sufficient quantity to disturb proper intercommunication between the various telephone sets at the various stations, which telephone sets consist of the transmitter 5, battery 6, induction coil 7, condenser 8, the switch-hook 9, and receiver 10. These telephone sets are bridged across the line circuit of the various stations. At the central station telephone, in addition to the telephone set A, shown, there are also provided two generators 11 and 12 having one terminal connected to the ground, and having keys 13 and 14, which are adapted, respectively, to connect either one generator or the other generator to the line conductors 1 and 2, thereby to send impulses over said conductors, which impulses are either of a positive or negative character, depending upon whether the key 13 or key 14 is depressed. These positive and negative impulses are designed to affect the polarized relays 15, which are likewise bridged across the line conductors 1 and 2, at the various substations to ground.

The polarized relays are provided with an armature 16, in association with contact

points 17 and 18, leading directly to wires 55 19 and 20, respectively, with an additional third wire 21 connected to the armature 16, itself. Thus, when positive currents are transmitted over the line conductors, contact point 17 is included in circuit to actuate the relay 22, thereby to step up the step-up mechanism 23, which step-up mechanism is provided with a contact lever 24, adapted to engage contact spring 25, when it is in the proper position, thus to operate a local signal 26. The arms 24 are, of course, in different positions angularly, so that the desired station can be called, depending upon the number of impulses transmitted over the line to actuate the relay 22. A local relay 27 serves to close the circuit through the signal 26. It will be apparent that the impulses to relays 22 must be short in duration, so that when station D, for instance, is wanted, the contact arms 24, in passing 75 their springs 25, at other stations, will not make contact long enough to permit the slow-acting relays 27 to close their circuits.

When negative impulses are transmitted over the line, contact 18 is included in the 80 circuit to actuate relay 28, which thereby releases the step-up mechanism 23, and allows it to come to normal through the agency of the spring 29. When the step-up mechanism comes to normal, it opens contact through the spring 30, thus preventing the further actuation by negative impulses of the relay 28. It will be seen from this that the polarized relay 15 has two coils, one coil 85 having a terminal connected to the line conductor 1, and the other coil having a terminal connected to the line conductor 2.

While I have herein shown and described the preferred embodiment of my invention, I do not limit myself to the particular construction I have shown, but having set forth 95 its most salient features, what I claim as new and desire to secure by Letters Patent is:

1. A selective signaling system comprising 100 a central station and a plurality of substations united by two line conductors, a step-by-step selector at each substation, electromagnetic means at each selector mechanism for operating same, having two coils, one 105 having a terminal connected to one line conductor and the other having a terminal connected to the other line conductor, contact-

points under the control of said electro-magnetic means, an operative inclusion of one contact point serving to step-up the step-by-step selector mechanism, and the operative inclusion of the other contact point serving to restore said selector mechanism to normal, magnets interposed between said contact points and said selector mechanisms, and a source of current at the central station for selectively operating said electro-magnetic means.

2. A selective signaling system comprising a central station and a plurality of substations united by two line conductors, a 15 step-by-step selector at each substation, electro-magnetic means at each selector for operating same, having two coils, one having a terminal connected to one line conductor and the other having a terminal connected 20 to the other line conductor, contact points under the control of said electro-magnetic means, an operative inclusion of one contact point serving to step up the step-by-step selector, and the operative inclusion of the 25 other contact point serving to restore said selector to normal, the selection of the desired contact point depending upon the polarity of the current from the central station, and sources of positive and negative 30 current at the central station for selectively operating said electro-magnetic means.

3. A selective signaling system comprising a central station and a plurality of substations united by two line conductors, a 35 step-by-step selector at each substation, electro-magnetic means at each selector for operating same, having two coils, one having a terminal connected to one line conductor and the other having a terminal connected 40 to the other line conductor, contact points under the control of said electro-magnetic means, an operative inclusion of one contact point serving to step up the step-by-step selector, and the operative inclusion of the 45 other contact point serving to restore said selector to normal, the selection of the desired contact point depending upon the polarity of the current from the central station, and magnets interposed between said 50 contact points and said selectors, and sources of positive and negative current at the central station for selectively operating said electro-magnetic means.

4. A selective signaling system comprising a central station and a plurality of substations united by two line conductors, a 55 step-by-step selector at each substation, electro-magnetic means at each selector for operating same, having two coils, one having a 60 terminal connected to one line conductor and the other having a terminal connected to the other line conductor, contact points under the control of said electro-magnetic means, an operative inclusion of one contact point serving to step up the step-by-

70 step selector, and the operative inclusion of the other contact point serving to restore said selector to normal, the selection of the desired contact point depending upon the polarity of the current from the central station, magnets interposed between said contact points and said selectors, local batteries 75 for operating said magnets, and sources of positive and negative current at the central station for selectively operating said electro-magnetic means.

5. A selective signaling system comprising a central station and a plurality of substations united by two line conductors, a 80 step-by-step selector mechanism at each substation, electro-magnetic means at each selector mechanism for operating same in bridge connection with the line conductors, contact points under the control of said electro-magnetic means, an operative inclusion 85 of one contact point serving to step-up the step-by-step selector mechanism, and the operative inclusion of the other contact point serving to restore said selector mechanism to normal, magnets interposed between said 90 contact points and said selector mechanisms, and a source of current at the central station for selectively operating said electro-magnetic means.

6. A selective signaling system comprising 95 a central station and a plurality of substations united by two line conductors, a step-by-step selector at each substation, electro-magnetic means at each selector for operating same in bridge connection with the 100 line conductors, contact points under the control of said electro-magnetic means, an operative inclusion of one contact point serving to step up the step-by-step selector, and the operative inclusion of the other contact 105 point serving to restore said selector to normal, the selection of the desired contact point depending upon the polarity of the current from the central station, and sources of positive and negative current at the central 110 station for selectively operating said electro-magnetic means.

7. A selective signaling system comprising 115 a central station and a plurality of substations united by two line conductors, a step-by-step selector at each substation, electro-magnetic means at each selector for operating same in bridge connection with the line conductors, contact points under the control of said electro-magnetic means, an 120 operative inclusion of one contact point serving to step up the step-by-step selector, and the operative inclusion of the other contact point serving to restore said selector to normal, the selection of the desired contact 125 point depending upon the polarity of the current from the central station, magnets interposed between said contact points and said selectors, local batteries for operating said magnets, and sources of positive and 130 negative current at the central station for selectively operating said electro-magnetic means.

negative current at the central station for selectively operating said electro-magnetic means.

8. A selective signaling system comprising a central station and a plurality of sub-stations united by two line conductors, a step-by-step selector mechanism at each sub-station, electro-magnetic means at each selector for operating same in bridge connection with the line conductors, contact points under the control of said electro-magnetic means, an operative inclusion of one contact point serving to step-up the step-by-step selector mechanism, and the operative inclusion of the other contact point serving to restore said selector mechanism to normal,

the selection of the desired contact point depending upon the polarity of the current from the central station, magnets interposed between said contact points and said selector mechanism, and sources of positive and negative current at the central station for selectively operating said electro-magnetic means.

In witness whereof, I hereunto subscribe my name this 19th day of January, A. D., 1909.

HARRY O. RUGH.
